(57) **CLAIM**

The ornamental design for a navigation bar for a browser-based user interface for an image processing machine, as shown and described.

DESCRIPTION

FIG. 1 is a front view of a navigation bar for a browser-based user interface for an image processing machine showing the design, the broken line drawing of a user interface is for illustrative purposes only and forms no part of the claimed design; and,

FIG. 2 is a front view thereof, on an enlarged scale, the navigation bar is shown separately for clarity of illustration.
